Primary Examiner — Kimberly Barnes(74) *Attorney, Agent, or Firm* — Downs Rachlin Martin PLLC(57) **CLAIM**

The ornamental design for a cycling helmet, as shown and described.

DESCRIPTION

FIG. 1 is a top front perspective of a cycling helmet showing our new design;

FIG. 2 is a bottom rear perspective view thereof;

FIG. 3 is a front view thereof;

FIG. 4 is a rear view thereof;

FIG. 5 is a side view thereof;

FIG. 6 is a second side view thereof;

FIG. 7 is a top view thereof; and,

FIG. 8 is a bottom view thereof.

The broken lines in the Figures are for the purpose of illustrating portions of the cycling helmet that form no part of the claimed design.

The shade lines in the Figures show contour and not surface ornamentation.
